(57) **CLAIM**

I claim the ornamental design for a roof vent assembly, as shown and described.

DESCRIPTION

FIG. 1 is a top perspective view of a roof vent assembly; FIG. 2 is a top view of the roof vent assembly of FIG. 1; FIG. 3 is a bottom view of the roof vent assembly of FIG. 1;

FIG. 4 is a front view of the roof vent assembly of FIG. 1; FIG. 5 is a rear view of the roof vent assembly of FIG. 1; FIG. 6 is a right side view of the roof vent assembly of FIG. 1, with the left side view being a mirror image of FIG. 6; FIG. 7 is a top perspective view of a second embodiment of the roof vent assembly of FIG. 1, the only difference being the configuration of the bottom flange;

FIG. 8 is a top view of the roof vent assembly of FIG. 7; FIG. 9 is a bottom view of the roof vent assembly of FIG. 7;

FIG. 10 is a front view of the roof vent assembly of FIG. 7; FIG. 11 is a rear view of the roof vent assembly of FIG. 7; and,

FIG. 12 is a right side view of the roof vent assembly of FIG. 7, with the left side view being a mirror image of FIG. 12.
